UNITED STATES PATENT OFFICE.

RUSSEL G. WOODWARD, OF WAUKEGAN, ILLINOIS, ASSIGNOR TO THE UNION SPECIAL SEWING MACHINE COMPANY, OF CHICAGO, ILLINOIS, A CORPORATION OF ILLINOIS.

STRIPPER-PLATE FOR SEWING-MACHINES.

SPECIFICATION forming part of Letters Patent No. 690,812, dated January 7, 1902.

Application filed September 1, 1899. Serial No. 729,195. (No model.)

To all whom it may concern:

Be it known that I, RUSSEL G. WOODWARD, a citizen of the United States, residing at Waukegan, in the county of Lake, State of Illinois, 5 have invented certain new and useful Improvements in Stripper-Plates for Ruffling-Machines, of which the following is a description, reference being had to the accompanying drawings and to the letters of reference 10 marked thereon.

My invention relates to an improvement in sewing-machines; and the especial object is to provide a stripper-plate for yoke-ruffling machines which shall be supported from above 15 and adapted to be raised as the presser-foot is raised.

In ruffling and sewing machines as ordinarily constructed the stripper-plate, which is used for the purpose of stripping the cloth 20 off the ruffling-teeth, is generally supported upon the bed-plate; but I have found that where certain kinds of work are to be done on machines of this character—as, for example, where the lower edge of a skirt is to be ruffled—this stripper-plate is in the way, and it 25 is desirable to support it from above, just as the ruffling-plate is supported, in order that the portions of the goods not ruffled may be passed beneath the presser-foot without being liable to be caught on the stripper-plate.

The invention therefore consists, primarily, in the sewing and ruffling machine having a stripper-plate attached to the frame of the machine and adapted to be lifted as the presser- 30 foot is lifted.

The invention is illustrated in the accompanying drawings, in which—

Figure 1 is a perspective view of so much of a "Union Special Yoke-Ruffling Machine" 40 as is necessary to an understanding of my invention, and Fig. 2 is a detached view of the stripper-plate.

In the drawings the needle-lever A, goose-neck B, ruffling mechanism C, cloth-plate D, 45 needle-bar E, presser-bar F, presser-foot G, needles a, and other parts are similar to those illustrated in my Patent No. 655,143, dated July 31, 1900.

h represents the stripper-plate, which is se-

cured by suitable screws b to the transverse 50 plate c, formed on the lower end of the angular arm I. This arm I, at a point near its upper end, is provided with a projecting sleeve through which passes a screw d, by which the stripper-plate is pivotally secured to a part of 55 the machine-frame. The blade h of the stripper projects beneath the toe of the presser-foot G, so that the presser-foot under the action of its spring tends normally to keep the stripper-plate down upon the work. When 60 it is desired to insert goods in the machine, it is also desirable to lift the stripper-blade h and to provide for its automatic lifting as the presser is lifted. A screw or lug e is provided on the supporting-arm of the stripper-blade 65 just above the presser-foot, so that when the presser-foot is raised it comes in contact with this lug or screw e and swings the arm I upwardly, thus raising the stripper-plate above 70 the work.

Having thus described my invention, what I claim as new, and desire to secure by Letters Patent, is—

1. In combination with the ruffling mechanism of a sewing-machine, a stripper-blade 75 attached to the framework of the machine independent of the cloth-plate and ruffling mechanism, and means for raising it above said cloth-plate; substantially as described.

2. In combination with the ruffling mechanism of a sewing-machine, an arm pivotally secured to the frame of the machine independent of the cloth-plate and above the same, a stripper-blade supported thereby, and means for moving said supporting-arm on its 80 pivot; substantially as described.

3. In a sewing-machine having a ruffling mechanism and a presser-foot with means for raising and lowering the presser-foot, a stripper-blade, an arm supporting the same pivoted to the frame of the machine above the cloth-plate, and having a projection extending into the path of movement of the presser-foot, whereby when the presser-foot is raised, it strikes the projection and raises the stripper-blade; substantially as described.

4. In a sewing-machine having a ruffling mechanism, and a presser-foot with means

for raising and lowering the presser-foot, a stripper-blade, a pivoted arm attached to the frame of the machine above the cloth-plate supporting the same, and having a projection offset from the vertical line of the pivot-point, and extending into the path of movement of the presser-foot, whereby when the presser-foot is raised, it strikes the projection and swings the stripper-blade-supporting arm on its pivot; substantially as described. 5

5. In a sewing-machine having a ruffling mechanism, and a presser-foot with means for raising and lowering the presser-foot, a stripper-blade, an arm pivotally secured on the machine-frame and supporting the said stripper-blade, and having a projection offset from the vertical line of the pivot-point, and extending into the path of movement of the presser-foot, whereby when the presser- 10 foot is raised, it strikes the projection and

swings the stripper-blade-supporting arm on its pivot, said stripper-blade normally projecting beneath the forward end of the presser-foot, and held thereby in engagement with the work; substantially as described. 25

6. In combination with the ruffling mechanism of a sewing-machine, an arm pivotally attached to the lower part of the overhanging arm or head of the machine, a stripper-blade supported thereby, and means operated by the movement of the presser-foot to swing said supporting-arm on its pivot; substantially as described. 30

In testimony whereof I affix my signature in presence of two witnesses.

RUSSEL G. WOODWARD.
